UNITED STATES PATENT OFFICE.

ALBERT M. PRICE, OF ELGIN, ILLINOIS, ASSIGNOR TO WM. WRIGLEY JR. COMPANY, OF CHICAGO, ILLINOIS, A CORPORATION OF WEST VIRGINIA.

LABEL-APPLYING DEVICE.

Original application filed March 3, 1919, Serial No. 280,283. Now Patent No. 1,491,970, dated April 29, 1924. Divided and this application filed May 6, 1922. Serial No. 558,930.

To all whom it may concern:

Be it known that I, ALBERT M. PRICE, citizen of the United States residing at Elgin, in the county of Kane and State of Illinois, have invented new and useful Improvements in Label-Applying Devices, of which the following is a specification.

The present invention relates to label applying devices and is particularly adaptable for applying labels or outer wrappers to individual sticks of chewing gum to which an inner wrapper has previously been applied.

A general object of the invention is to provide certain new and useful improvements in the construction and mode of operation of devices of the above named character to adapt them for the performance of their functions in a more practical, efficient, and reliable manner.

A more particular object of the invention is to provide improved mechanism for applying glue to the labels.

To the accomplishment of these objects and such others as may hereinafter appear, as will be readily understood by those skilled in the art, the invention comprises the features and combination of parts hereinafter described and particularly pointed out in the appended claims.

The invention is shown as applied to the wrapping machine illustrated and described in a co-pending application Serial Number 280,283, filed March 3, 1919, by the present inventor, and from which the present application has been divided. The invention however, is not limited in its use to the type of machine illustrated.

In the accompanying drawings,—

Fig. 1 is a vertical sectional view of the preferred embodiment of the invention, together with so much of the wrapping machine of the co-pending application above referred to as is necessary to illustrate the application of the present invention thereto:

Fig. 2 is an enlarged sectional view taken substantially on line 2—2 of Fig. 1; and

Fig. 3 is an enlarged elevational view of the label guide rod.

Figs. 4, 5, 6 and 7 show successive steps in the folding of the label around the article.

The mechanism shown in the drawings is adapted to operate upon articles such as

sticks of chewing gum which are supplied thereto by means disclosed in the above mentioned application, Serial No. 280,283, said means operating to fold an inner wrapper around the sides, longitudinal edges and ends of the gum sticks and deliver them to the illustrated mechanism. The mechanism herein illustrated operates to complete the folding of the inner wrapper about the gum sticks and then to apply another wrapper or label outside of the first wrapper. After being wrapped and labeled, the gum sticks are ready to be stacked and packaged, if desired.

Referring to Fig. 1, the mechanism therein shown comprises, in general, a charging table 23 across which a stick of gum, partially enclosed by an inner wrapper, is advanced while the operation of applying said wrapper is completed by suitable folding devices associated with the table; transporter members 78 arranged in longitudinal slots 75 in the charging table and movable through orbital paths to advance the gum sticks; means including a pair of cooperating feed rolls 146 and 147 for feeding a label or outer wrapper in front of the gum sticks 60 at the delivery end of the charging table; an intermittently rotatable drum 100 secured to a shaft 101 and having longitudinal pockets 102 that are successively positioned to receive the gum sticks as they leave the charging table together with labels which are folded over the sticks as the latter are forced into the drum pockets; a receiving table 222 to which the wrapped and partially labeled sticks are transferred from the drum pockets 102; a glue applying mechanism including a plurality of glue rolls 175 and a movable guide-rod 189 which moves the ends of the labels into contact with the glue rolls as the former are advanced into the field of operations of said guide-rod; transporter members 224, analogous in construction and mode of operation to the transporter members 78, and movable through longitudinal slots in the table 222, 100 for removing the wrapped and labeled articles from the drum 100 and advancing them along said table, and beneath a plate 241 that is supported immediately above the table, said operation resulting in bringing 105 the opposite ends of the labels together;

and devices 241^a carried by the plate 241 for forcing the gum sticks against the table 222 to hold the label ends together under pressure during their initial gluing contact.

5 All of the parts above mentioned, have substantially the same construction and mode of operation as that of corresponding parts illustrated and described in said co-pending application, Serial No. 280,283.
10 Therefore, only a brief and general description of the common features of the two machines will be given, reference being had to said application for a more detailed description, if desired.

15 The sticks of gum with their inner wrappers completely applied are advanced into the pockets of the drum 100 by the action of the transporter members 78. These members consist of two flat vertical plates rigidly connected in spaced apart relation by means of tie-rods 77. Each transporter member 78 has three propulsion fingers 80, 81 and 82 which enter the slots in the table 23 to engage and advance the sticks resting thereon. The transporter members 224 which remove the wrapped and labeled sticks from the drum 100 and feed them along the table 222, are rigidly connected in spaced relation by tie rods 226 and 227 and are severally rigidly connected by longitudinal beams, one of which is shown at 76 in Fig. 1, with the transporter members 78. The entire transporter structure is mounted upon crank pins 85 and 86 extending from crank-arms 87 and 88 secured to shafts 89 and 90. These shafts are rotated in unison in a counter clockwise direction so that the fingers of the transporter plates 78 and 224 will be repeatedly raised and carried through the slots in the tables 23 and 222 to propel the gum sticks step-by-step along said tables.

40 The drum 100, which receives the sticks as they leave the charging table, is of cylindrical form and has a plurality of tangential pockets 102 for holding the wrapped sticks of gum. In order that the pockets 102 shall be successively positioned to receive the gum sticks from the charging table, the drum is rotated intermittently. To this end, the drum is connected with a shaft 26 through a train of gearing comprising a gear 259 fast on the shaft 101, an idler gear 258 and a gear 257 that is fixed to the shaft 26. Secured to the shaft 26 is a disk 254 carrying upon one of its faces four triangular plates 255 arranged to provide four radial cam passageways 256. The cam passageways 256 are adapted to be acted upon by rollers 253 carried by a gear 250 that is fast upon a continuously rotating shaft 251. With this construction, the drum 100 is rotated intermittently and through ninety degrees at each step movement thereof.

45 60 65 The labels which are to be fed in front of the gum sticks just before the latter are

loaded into the pockets of the drum 100 are contained in a magazine 114 and are removed, one at a time, from the bottom of the magazine by a dispensing roll 116 and are introduced thereby between a pair of feed rolls 146 and 147. The rolls 146 and 147 are geared together and intermittently driven from the drum shaft 101 through a gear 273 on said shaft which meshes with the gear on the shaft of the feed roll 147. After passing between the feed rolls 146 and 147 each label is guided downwardly by guide blocks 162 and thereafter it is received between the roller 147 and the cylindrical surface of the drum 100. The label is then fed downwardly between the drum 100 and the end of table 23 to the position shown by dotted lines in Fig. 1 preparatory to receiving a wrapped stick from said table. When the label has been fed into this receiving position, the drum 100 will be at rest with one of its pockets 102 positioned in horizontal registration with passageway above the table 23. The fingers 82 of the transporter mechanism will then shift the wrapped gum stick against the label end to fold such end around the stick and to carry the stick into the drum pocket. The drum has peripheral concave sections 165 which come opposite the feed roll 147 to release the label end so that it will be free to be folded into the drum pocket with the gum stick as shown in Fig. 4. After the stick has been charged into the drum, the drum is rotated to carry the free end of the label through the gluing field.

60 65 70 75 80 85 90 95 100 105 110 115 120 125 130 The application of glue to the wrapper end is accomplished by improved glue-applying mechanism which is described and claimed in this application. This mechanism includes a rectangular glue receptacle 166 which is detachably supported on the machine frame, the frame having at one side the horizontal slots 167 for receiving pins 168 extending from the glue receptacle, while at the other side the frame has a vertical slot 169 for receiving a pin 170 extending between lugs 171 projecting from the glue container. The upper end of the slot is of a diameter to fit the pin, but the throat of the slot is narrow to receive only the reduced diameter sections 172 of the pin. The pin is slideable in its supporting lugs and after the pins 168 are inserted in the horizontal slot 167, the pin 170 is shifted to bring the reduced section 172 into registration with the slot 169 and then when the receptacle is shifted upwardly to bring the pin into the end of the slot, the pin is shifted longitudinally to displace the reduced section from the slot throat and the glue container will then be rigidly held in operative position. At one side the container has the slide 173 for permitting the charging of glue into the container, while at the

other side are openings 174 through which project the glue-applying rolls or disks 175 supported and spaced on the shaft 176 journaled in bearings mounted on the glue receptacle. Secured to the glue disk shaft 176 is a ratchet disk 178 with which a pawl 179 cooperates. This pawl is pivoted by a pin 180 at the outer end of the arm 181 extending from the hub 182 bearing on shaft 183 which extends transversely of the machine and is journaled in a bearing hub 184. Secured to the shaft in front and in rear of the hub 182 are the hubs 185 and 186 from which arms 187 and 188 extend upwardly to support the label guide rod 189 which is parallel with the shaft 176 and adjacent the glue-applying disks 175. On brackets 190 and 191 extending upwardly and diagonally from the arms 187 and 188 a stripper plate 192 is supported in such manner as to be slidable forwardly and rearwardly to be removed from the machine or inserted in operative position on the brackets. The lower end of the stripper plate is between the rod 189 and the peripheries of the glue-applying disks 175 and has notches 193 registering with the disks, while the rod 189 has peripheral notches 194 in registration with these stripper plate notches and disks. The arms 187 and 188 with the rod and plate supported thereon are adapted to be swung toward or away from the glue-applying disks. Depending from the hub 186 is the arm 195 which at its lower end has the forwardly extending abutment lug 196. Depending from the hub 182 is the arm 197 which near its lower end has the laterally extending arms 198 and 199 terminating in inwardly extending flanges 200 and 201. Through these flanges and slidable therein extend abutment rods 202 and 203 having at their inner ends the abutment heads 204 and 205 and having at their outer ends adjusting nuts 206 and 207. Between their abutment heads and their respective flanges the rods support compression springs 208 and 209. The function of the mechanism just described is that the arm 195 may be positively operated back and forth with a force equivalent to the tension on the springs 208 and 209, but should a resistance be encountered by any of the parts carried on the upper ends of the arms 187 and 188, due to materials dislodged from their regular course through the machine, or from other causes, then the springs 208 and 209 will alternately yield, and the arm 197 may oscillate without transmitting its motion to the arms 187 and 188, thus preventing damage to the various mechanisms involved. A frame part 210 connects the left end of arm 198 with the end of arm 181, to which arm 181 the pawl 179 is pivoted. For yieldingly holding the upper end of the pawl against the ratchet 178 the compression spring 211

is provided in the pocket 212 of the frame part 210 and presses against the lower end of the pawl.

At its lower end the arm 197 is pivoted to one end of a connecting link 213, which link pivots at its other end to the arm 214 on shaft 215, this shaft at the rear of the machine having the upwardly extending arm 216 connected with the arm 217 extending from the eccentric strap 218 which encircles the eccentric disk 219 on the shaft 89. As this shaft 89 rotates the arm 197 with its abutment frame thereon will be oscillated laterally to positively swing the arm 181 and to operate the pawl for advancing the glue applying disks. Through the flexible abutment rods acting on the lug 196, the arm 195 and hub 186 may be oscillated, and this hub being secured to the shaft 183 such swing of the arm 195 will be communicated to the hub 185 which is also fixed upon the shaft 183 and the arms 187 and 188 will swing to operate the rod 189 and plate 192 with reference to the glue-applying disks.

The free ends of the labels projecting from the drum 100 after reception of the gum sticks will extend downwardly between the drum and the stripper plate 192 as shown by dotted lines in Fig. 1 and also as in Fig. 4, and after a ninety degree rotation of the drum, after receiving a stick, the label end will be projected between the stripper plate and the rod 189 into position to receive glue from the glue-applying disks at points slightly removed from the lower edge of the label. As the glue-applying disks are rotated by the pawl and ratchet mechanism fresh glue will be available on their peripheries for each label, and after the label has been positioned between the plate 192 and rod 189, the arms 187 and 188 are swung, and the stripper plate 192 and rod 189 are moved thereby, toward the disks which then project through the slots 193 of the plate and against the label for applying short streaks of glue *g* as shown in Fig. 5 thereto. It is to be noted that the glue is taken off from the peripheries of the rollers by contact, i. e., there is no wiping of the glue-applying disks over the label or of the label across the disks. This feature tends to insure uniformity in the glue-applying operations upon successive articles and to prevent undesirable misplacement or smearing of the glue. After the glue has been applied to the label the arms 187 and 188 are swung in the opposite direction to shift the stripper plate 192 to raise the label away from the glue disks to prevent smearing of the glue across the edge of the label as the latter is moved away from the glue-applying device by the next partial rotation of the drum 100. During the rotation of the drum, the glued label end is drawn over the top of the rod 189 and through that portion of

the passageway 221 which lies between the drum and the end of a receiving table 222, the drum again coming to rest when its pocket, which contains the stick with the glued label, is in horizontal registration with the passageway between the top of the table 222 and the plate 241.

The fingers of the transporter members 224 then engage the gum stick and shift it onto the table into position beneath the plate 241, and the extending end of the label to which the glue has been applied will be pressed against the other end of the label and the label thus secured as shown in Fig. 6. As the transporter structure continues to operate, the completely wrapped and labeled gum sticks will be fed along the table 222 and they may be subsequently stacked and bundled, if desired.

It has been the practice heretofore, to apply the glue substantially at the edge of the label so that when the meeting edges were brought together, the glue would be forced out or wiped across the label at a point beyond the overlapping edge and become smeared across the face of the label. As a result of this practice the individually wrapped sticks would adhere to one another so that a person would be unable to easily remove a single stick of gum from a package without first completely breaking open the package in order to separate the sticks. By applying the glue as above described at points somewhat removed from the edge of the label and by making provision for preventing the glue from being smeared across the edge of the label after it has been applied, the inventor has made an advance in the art which results in the production of an improved package from the point of view of neatness and which insures against possibility of the individual sticks adhering to one another.

It is evident that changes and modifications may be readily made in the construction and arrangement of the parts without departing from the scope of the invention, and it is to be understood that the invention is not limited to the construction and arrangement of parts shown and described except so far as defined in the following claims.

What is claimed is:

1. In a label-applying device, a glue roll, a guide member adjacent the periphery of the glue roll, means for holding an article having wound thereabout one end portion of a label in process of being applied thereto and advancing the article and label to introduce the free end of the latter between said guide member and the glue roll, means to carry the free end of the label against the glue roll, and means for folding the glued end of the label against the opposite end thereof to secure the label to the article.

2. In a label-applying device the combination of a drum provided with a pocket for holding an article having a label wound partly thereabout with the free end of the label extending outside of the drum pocket, a row of glue applying disks adjacent the drum, a rod arranged adjacent the path of the extending label end, means for moving the rod to press said label end against the glue applying disks and then to release the label, and means for removing the article from the drum pocket and folding the glued end of the label against the other end thereof.

3. In a label-applying device the combination of a glue applying disk, a rod and a plate in front of said glue applying disk, said plate having slots registering with the disks and adapted to receive the latter, means for holding an article having a label partially wound thereabout with the free end of the label extending therefrom and advancing the article to introduce said extending end of the label between said rod and plate, means for bodily shifting said rod and plate toward said glue applying disk whereby said extending end of the label is pressed by the rod against said disk to receive glue therefrom, and means for releasing the article from the holding means and folding the glued end of the label against the article.

4. In a label applying device the combination of a row of glue applying disks, a glue pot in which the glue disks are partially submerged, a rod and a plate in front of said glue-applying disks, said plate having slots registering with the disks and adapted to receive the latter, means for holding an article having a label partially wound thereabout with the free end of the label extending therefrom and advancing the article to introduce said extending end of the label between said rod and plate, means for bodily shifting said rod and plate toward the glue applying disks whereby said extending end of the label is pressed by the rod against the disks to receive glue therefrom and for rotating the glue disks to replenish the supply of glue on the exposed portions thereof, and means for releasing the article from the holding means and folding the glued end of the label against the article.

5. In a label-applying machine, the combination of an adhesive-applying device, means for partially winding a label transversely around an article with a free end of the label extending therefrom and for moving said free end to a point adjacent said adhesive applying device, means movable in one direction for engaging the free end of the label and moving it into non-wiping contact with said device to receive adhesive therefrom adjacent its marginal edge, and means movable in the opposite direction for stripping the label end from said device.

6. In a label-supplying machine, the combination of an adhesive-applying device, means for partially winding a label transversely around an article with a free end of the label extending therefrom and for moving said free end to a point adjacent said adhesive applying device, spaced label engaging and guiding means between which the end of said label is carried so as to be 5 out of contact with said adhesive applying device, said engaging means being movable to press the label adjacent its end positively into engagement with said device to receive adhesive, said parts being constructed and 10 arranged to insure that the adhesive will be applied at a point removed from the edge of the label end. 7. In a label-applying machine, the combination of an adhesive-applying device, means for partially winding a label transversely around an article with a free end of the label extending therefrom and for moving said free end to a point adjacent said adhesive applying device, spaced label-engaging 15 and guiding means between which the end of said label is carried so as to be out of contact with said adhesive applying device, said engaging means being movable to press the label end positively into engagement 20 with said device to receive adhesive and said guiding means being movable to strip the label end from said members, and said parts being constructed and arranged to insure that the adhesive will be applied at a point 25 removed from the label end and that it will not be smeared toward said edge during 30 the stripping operation. 8. In a label-applying machine, the combination of a charging table, a drum near 35 said table having a pocket, means for rotating said drum to intermittently bring said pocket into registration with said table, means for feeding a label between said pocket and table, means for shifting an article from said table toward and into said pocket whereby one end of said label is 40 shifted with the article into the pocket and wrapped partly around the article, a glue applying disk, a bar arranged adjacent the path of the extending end of the label, means 45 for shifting said bar to carry the label end against the glue applying disk and then to release such end, means for discharging the article from the drum, and folding 50 mechanism for folding the glued end of the label against the other end of the label. 9. In a label-applying machine, the combination of a drum having a pocket, means 55 for feeding an article and one end of a label into said pocket to partially fold the label around the article with its other end outside of the drum, means for rotating said drum, a glue applying disk, a rod and a 60 plate in front of said glue applying disk between which the extending end of the 65 label is projected during rotation of the drum, means for bodily shifting said rod and plate toward the glue applying disk and said plate having slots for receiving the disks whereby the end of the label is 70 pressed by the rod against the disk to receive glue therefrom, and means operative after further rotation of the drum to eject the article and to wrap the glued end around it during such ejection. 75 10. In a label-applying machine, the combination of a drum having a pocket therein, means for feeding an article and one end of a label into said pocket to partially fold the label around the article and to leave the other end outside of the drum, means for rotating said drum, glue-applying disks adjacent said drum, a rod and a plate parallel with said drum and the disk axis, arms on which said rod and plate are supported, said rod and plate being normally in front of the disks in position to receive the extending end of the label between them, said plate having slots in registration with said disks, means for swinging said arms to carry the lower end of the plate past the disk peripheries and to cause the rod to press the trailing label end against the disks for the reception of glue, the swinging of said arms to restore the rod and plate to their normal position thereby causing said plate to strip the label end from the disks, means for ejecting the article from the drum after further rotation thereof, and folding means for folding the glued end of the wrapper toward the article and against the other end of the wrapper. 80 85 90 95 100 105 110 115 120 125 130
11. In a label-applying machine, the combination of a drum and means for causing intermittent rotation thereof, said drum having pockets, means for feeding articles into said pockets and one end of labels to be partially wound about the articles with their outer ends extending from the drum, a row of glue-applying disks adjacent the drum, a rod and a plate between the drum and the disks separated by a gap, means for swinging said rod and plate toward and away from said disks, said plate having slots through which the disk peripheries may project when the plate and rod are moved toward the disks, the extending ends of the label's being inserted between said rod and plate during rotation of the drum so as to be carried by the rod against the disks to receive glue when the rod and plate are moved toward the disks and to be stripped from the disks by the plate when the latter is moved away from the disks, means for ejecting the articles from the drum pockets, and means for folding the glued extending ends of the label against the article. 120
12. In a label-applying machine, the combination of a drum having a pocket, means for simultaneously feeding an article and one 130

end of a label into said pocket with the other end of the label extending outside of the pocket, a row of glue applying disks adjacent the drum, supporting arms adapted 5 to swing, a rod and a plate secured to said arm between said drum and disks and separated by a gap, driving mechanism, means for causing the swinging of said supporting arms to carry said rod and plate toward and 10 away from the disk axis, said plate having slots in registration with said disks, said rod and plate being normally in position to receive the extending end of the label in said gap whereby when said arms are swung said 15 plate will be carried past the disk peripheries and said rod will press the label end against the disk peripheries to receive glue therefrom, return movement of the rod and plate to normal position causing said plate 20 to remove the glued label end from the disks, means for discharging the article from the pocket, and folding means for folding and securing the trailing label end to the other label part.

25 13. In a label-applying machine, the combination of a drum having a pocket, means for simultaneously feeding an article and one end of a label into said pocket with the other end of the label extending outside of 30 the pocket, a row of glue applying disks adjacent the drum, supporting arms adapted to swing in opposite directions, a rod and a plate secured to said arm between said drum and disks and separated by a gap, driving 35 mechanism, and spring connections between said driving mechanism and said supporting arms for causing the swinging of said arms to carry said rod and plate yieldingly toward and from the disk axis, said plate having 40 slots in registration with said disks and said rod and plate being normally in position to receive the extending label end in said gap whereby when said arms are swung in one direction said plate will be carried 45 past the disk peripheries and said rod will press the label end against the disk peripheries to receive glue therefrom, and when said arms are swung in the opposite direction said plate will strip the glued label 50 from the disks.

55 14. In a label-applying machine, the combination of means for holding an article having a label partially wound thereabout with one end of the label extending therefrom and advancing the article to bring the extending label adjacent its end to a predetermined position, and means for applying adhesive to said extending label end at a point removed from the edge thereof.

60 15. In a label-applying machine, the combination of means for holding an article

having a label partially wound thereabout with one end of the label extending therefrom and advancing the article to bring the extending label end to a predetermined position, an adhesive-applying roll, and means for moving said label end relatively to said holding means to bring the face of said label end squarely into contact with a point on the periphery of the roll and to remove it from the roll without permitting it to wipe across said periphery.

65 16. In a label-applying machine, the combination of an adhesive-applying roll, means for holding an article having a label partially wound thereabout with one end of the label extending therefrom and advancing the article to position the label end adjacent said roll, and means for moving the label end into non-wiping contact with the periphery of the roll to receive adhesive and thereafter removing the label end from the roll in a direction substantially opposite to that in which it was moved into contact therewith.

70 17. In a label-applying machine, the combination of an adhesive-applying roll, means for holding an article having a label partially wound thereabout with one end of the label extending therefrom and advancing the article to position the label end adjacent said roll, and means for engaging successively the opposite faces of the label end to move said end in flatwise directions first 75 into contact with the periphery of said roll and then out of contact therewith.

75 18. In a label-applying device, a glue roll, means for holding an article having wound thereabout one end portion of a label in process of being applied thereto and advancing the article so that the free end of said label is disposed adjacent said glue roll, means for moving the free end of said label into contact with said glue roll, means for moving and holding the label from contact 100 with the glue roll and means for folding the glued free end of the label above the article.

105 19. In a label-applying device, a glue roll, means for holding an article having wound thereabout one end portion of a label in process of being applied thereto, and advancing the article so that the other end of said label is disposed adjacent said glue roll, means for moving the said end of the label into contact with said glue roll, means for moving and holding the label from contact 110 with the glue roll and means for folding the glued end of said label about the article.

115 In testimony whereof I have affixed my signature.

ALBERT M. PRICE.
